UNITED STATES PATENT OFFICE.

CHARLES F. MARKHAM, OF PROVIDENCE, RHODE ISLAND.

PIN.

1,079,015.

Specification of Letters Patent. Patented Nov. 18, 1913.

Application filed November 4, 1911. Serial No. 658,505.

To all whom it may concern:

Be it known that I, CHARLES F. MARKHAM, a citizen of the United States, residing at the city of Providence, in the county 5 of Providence and State of Rhode Island, have invented certain new and useful Improvements in Pins, of which the following is a specification, reference being had therein to the accompanying drawing.

10 This invention relates to pins of the class commonly known as beauty or cuff pins, and has for its object to provide a so-called one-piece pin, the same having its joint and its catch member formed integral with the 15 body portion thereof and yet of thicker or heavier stock than that of which the body portion is formed so that a pin formed of precious metal need not all be of heavy stock in order to obtain the necessary 20 strength at the points where strength is required.

The invention further consists in forming a tongue integral with the end of the body portion the same being slotted and bent over 25 toward the opposite end of the pin and back upon itself with its end extending into the hollow body of the pin and resting against the bottom of the pin body a loop being formed in the bend for the reception of a 30 T-head pin stem.

The invention still further consists in providing lateral extensions near the end of this member so that when the same is drawn over into position to form the joint 35 member, the edges of the pin body may be rolled over these laterally extending portions on either side to lock the same firmly in position within the pin body.

With these and other objects in view, the 40 invention consists of certain novel features of construction, as will be more fully described and particularly pointed out in the appended claims.

Of the accompanying drawings: Figure 1 45 is a side elevation showing a pin having a joint and a catch member of my improved construction. Fig. 2 is a plan view of my improved pin. Fig. 3 is a plan view illustrating the general shape of the blank having 50 extending portions at either end from which the joint and catch members are formed respectively. Fig. 4 is a side elevation illustrating the extending end portions, and the main body portion as having been 55 reduced in thickness or made thinner than that of said end portions. Fig. 5 is an en-

larged side elevation partly in section illustrating the general construction of my improved joint member. Fig. 6 is an end view sectioned on line 6—6 of Fig. 5 looking in 60 the direction of the arrow and illustrating the edge of the body rolled over that of the lateral extension for locking the end of the joint member into the pin body.

My present invention relates more particularly to a so-called one-piece pin and in the drawings of which 1 designates the body thereof, 2 the joint member, and 3 the catch member, both of which latter are formed integral with said body portion. 65

In the construction of pins from high grade or expensive material, such as solid gold, silver, heavy rolled plate stock or the like, the body portion may be made very light or thin and still, owing to its cupped 70 shape be sufficiently strong and durable for all practical purposes. When a cuff-pin is constructed of such thin stock it has heretofore been found necessary to form the joint ears and catch member separately and 75 of heavier stock and to solder the same to the body, as when they were made all in one piece with the body portion, they were so thin and light that they were not practical being easily broken off and the pin destroyed and in order to obtain this strength 80 at the points desired the body portion would be much thicker than was necessary, thus 85 unnecessarily increasing the cost of the pin.

In order to obviate the above difficulties 90 and yet form the joint integral with the body portion I have reduced the body portion in thickness forming the same extremely thin and light and at the same time leaving that portion from which the joint is formed, 95 of a thickness sufficient to obtain the desired strength and stiffness to withstand the necessary strains.

As illustrated in Figs. 3 and 4 an outwardly extending tongue 4 is formed on one 100 end of the body portion 1, the same being cut away or recessed at 5—5 forming laterally extending portions 6 having shoulders 7. A slot 8 is also punched or otherwise formed through this tongue for the reception 105 of the pin stem 9. Another tongue 10 extends outwardly from the opposite end of the pin body from which the catch member 3 is formed. The joint tongue is just enough thicker than the body portion to insure 110 the proper amount of strength which is required to serve as practical joint and

catch members, the body portion having been reduced to the thinness required by rolling, swaging, or otherwise. After having thus formed the blank the same is struck 5 forming the body portion into a cupping to form the tongue 6 being bent inward or toward the opposite end of the pin body and back upon itself as shown at 11 in Fig. 5, the end 12 of this tongue resting adjacent and 10 being supported on the bottom 13 of the pin body or shell. A loop 14 is formed at the bend which with the slot 8 formed therethrough provides a pair of ears 15—15 adapted to receive the T-shaped end of the 15 pin stem 9. By resting the end of this joint member against the bottom of the pin body a strong and rigid support is obtained to prevent movement when the pin stem engages and rests upon its fulcrum point at 16 20 for the purpose of obtaining a tension when its pointed end engages the catch member 3. The broad side face of this end portion extends into the hollow body portion and is arranged to lie adjacent to and parallel with 25 the inner face of the end wall of the pin body, which is a very neat, practical and effective way of disposing of and securing the free end of this joint member.

In order to more firmly secure this tongue 30 end 12 the edges 17 of the pin body may be rolled over the laterally extending shoulders 7 of this tongue thereby firmly and rigidly locking the same in position in the pin body without the use of solder.

35 During the construction of my improved pin the head of the pin stem is inserted into position before the end 12 of the joint member is secured in position within the body of the pin.

40 My improved construction of joint may be used on pins of any shape, but the same

has its greatest advantage when used on pins substantially rectangular in shape and having practically square ends.

I claim:

1. A pin of the character described comprising a cupped body portion having an integral joint member formed at one end, said joint member being bent over and back toward the opposite end of the body to form 50 a loop to receive the head of a pin stem, the wall of said loop being provided with an opening through which the shank of the pin stem may extend, the free end of said joint member extending down into the cupped portion of said body, the face of the bent over portion lying against the inner face of the end wall of the cupped portion of said body.

2. A pin of the character described comprising a cupped body portion having an integral joint member formed at one end, and provided with shoulders, said joint member being bent over and back toward the opposite end of the body to form a loop 65 to receive the head of a pin stem, the wall of said loop being provided with an opening through which the shank of the pin stem may extend, the free end of said joint member extending down into the cupped portion 70 of said body, the face of the bent over portion lying against the inner face of the end wall of the cupped portion of said body, the edges of the side walls of said body being bent over said shoulders.

In testimony whereof I affix my signature in presence of two witnesses.

CHARLES F. MARKHAM.

Witnesses:

HOWARD E. BARLOW,
E. I. OGDEN.
